UNITED STATES PATENT OFFICE

2,338,776

GARMENT STEAMING AND DRYING DEVICE

Edward A. Miller, Milwaukee, Wis., assignor to
 United States Hoffman Machinery Corporation,
 New York, N. Y., a corporation of Delaware

Application June 12, 1940, Serial No. 340,217

10 Claims.

(Cl. 223—70)

My invention relates to garment steaming and drying devices, and more particularly to a type of device that will give the proper shape to the garment during and after the process.

The object of my invention is to provide a means of permitting dry steam to pass through every portion of the fabric of the garment thereby renovating the nap of the fabric.

Another object of my invention is to provide a means of preventing condensation from passing through the garment by causing superheated dry steam only to impregnate the fabric.

Still another object of my invention is to cause pre-heated air to dry the garment in substantially its original shape to fit the form of the wearer, in a manner to eliminate all wrinkles, by means of an inflated envelope or covering over the garment form, thereby permitting adjustment of the garment to various sizes over the same form.

A still further object of my invention is to provide such a device that can be satisfactorily adjusted and manipulated by a single operator, permitting the entire operation to be performed in a minimum length of time.

Other and further objects of my invention will become more apparent as the description proceeds, when taken in conjunction with the drawings in which

Figure 1 is a fragmentary cross-sectional view of the entire device illustrating the combination of features comprising the device,

Figure 2 is a perspective view of the device having a garment placed in position ready for processing,

Figure 3 is a perspective view of the steam chamber or separator and distributing unit, and

Figure 4 is a plan view of the air blast damper arrangement.

Similar characters of reference indicate corresponding parts throughout the several views, and referring now to the same, the character 10 illustrates a hollow perforated metal body form representing the torso and bust of a person, this body form 10 is rotatably mounted on a cylindrical portion 11 forming a part of a warm air chamber 12, by means of outwardly projecting members 13 attached to an annular support rim 14.

The entire body form 10 is enveloped by an inflation bag 15 made of a closely woven pliable material such as taffeta silk. The bag 15 is provided with auxiliary bag like members 16 open at their point of contact with the inflation bag 15

and closed at their depending ends 17 as shown. The lower end of the bag 15 is clamped between an annular flange 18 and flange 18' which together are rotatably mounted on the conical top of the chamber 12.

Centrally disposed within the body form 16 is a steam chamber 19 equipped with a steam inlet tube 20 at its lower end and an outlet tube 21 at its upper end. At the extreme bottom of the steam chamber 19 is a drain 22. Above the steam inlet tube 20, at a point near the center of the steam chamber 19 is a perforated baffle 23 which acts as a separator for the condensation from the steam, permitting only dry steam to pass through the outlet tube 21 and causing the condensation to drain through the outlet 22 at the bottom of the chamber 19.

The pre-heated steam enters through the tube 24 and the condensed steam returns to the source of supply through the tube 25.

The outlet tube 21 on the upper end of the steam chamber 19 is provided with a spring actuated valve shown at 26 and the steam is led from this valve 26 through a plurality of downwardly disposed tubes 27 closed at their lower ends 28, and provided with a plurality of apertures 29 facing inwardly toward the outer wall of the steam chamber 19. The valve 26 is also provided with a series of link rods 30, 30', 30" supported at 31 and 32 on the wall of the warm air chamber 12 and terminating into a foot pedal 33 to be employed when the valve 26 is to be opened thereby permitting the steam to be forced outward through the apertures 29 in the tubes 27.

There is a blower unit 34 actuated by a motor 35 shown encased within the warm air chamber 12. The air inlet to the blower 34 is connected to a radiator unit 36 in the outer wall of the warm air chamber 12 the air being drawn in from the outside through the radiator 36 and forced through the outlet 37 of the blower 34 into the warm air mixing chamber 12. In Figure 1 it will be noted that the steam enters the top of the radiator unit 36 from the tube 24 and exhausts at the bottom into the tube 25. Obviously the air entering the blower unit 34 through the radiator unit 36 is heated to a pre-determined temperature before being exhausted into the mixing chamber 12.

Immediately above the blower 34 within the chamber 12 is a partition 38 equipped with a plurality of apertures 39. This partition 38 is also provided with a revolving perforated damper plate 40 pivotably attached to the partition 38.

at 41. A lever 42 attached to the outer edge of the damper plate 40 extends outward through the wall of the chamber 12 and permits the operator to revolve the damper plate thereby causing the apertures 39 in the partition to register with the apertures 43 in the damper plate. This arrangement is shown in the plan view shown in Figure 4.

In Figure 2 is shown a perspective view of the device showing a garment 44 in position over the inflated bag 15 supported by the body form 10, and illustrating the manner in which the bag like members 16 engage the sleeves of the garment. There is also shown a bracket 45 mounted on the outer wall of the chamber 12 at 46. This bracket 45 hingedly supports a retaining clamp 47 at 48 which clamp is employed to retain the garment 44 in a closed and proper position. Figure 2 also shows the cord 49 equipped with an attaching plug 50 to lead the current from the source of supply to the motor 34 within the enclosure 12.

In operation the device functions as follows. A garment 44 is placed over the inflation bag 15 supported by the body form 10. The clamp 47 assists in keeping the garment in position. The operator opens a valve in the steam supply line 24 which permits live steam to enter the steam chamber 19 at 20. In entering the steam contacts the baffle plate 23 and the condensation is permitted to drain out of the chamber 19 through the tube 22. When the operator presses on the foot pedal 33, the valve 26 on the upper end of the chamber 19 is actuated by means of the link arrangement 30, 30', and 30'' thereby permitting the steam to be forced out of the apertures 28 in the downwardly disposed tubes 27. This process fills the entire inflation bag 15 with dry steam which, due to the pressure exerted, passes through the bag 15 and impregnates the fabric of the garment 44 causing the nap to loosen outward. Obviously, the auxiliary bag members 16 having been inserted into the sleeves of the garment also permit the steam to engage the fabric of the sleeves. The entire body form 10 supporting the garment 44 may be revolved to permit access to any part of the garment by the operator. After sufficient steam has been forced through the fabric to thoroughly eliminate all foreign matter, the operator closes the steam supply and places the motor 34 in operation by means of a switch not shown. This will cause the blower 34 to draw in air through the steam heated radiator unit 36 forcing the warmed air into the chamber 12. Upon rotating the damper plate 40 by means of the lever 42, the warm air will be forced from the chamber 12 through the apertures 39 and 43 into the inflation bag 15 and auxiliary bags 16 thereby causing the bag to expand to the full size of the garment 44, and permitting dry warm air to pass through the fabric of the garment. The operator manually adjusts the garment eliminating any possible wrinkle or the like that might be present. The warm air will have a tendency to thoroughly dry the fabric in its natural position leaving the nap extended and fluffy.

In the chosen embodiments of my invention there are features not heretofore disclosed in the prior patent art. I do not wish to be limited however to the exact features portrayed in the drawings or description, for many changes can be made in the construction of the device without departing from the spirit of the invention as outlined by the appended claims.

Having thus described my invention, what I claim and desire to secure by Letters Patent in the United States is:

1. A device of the character described comprising in combination a body form, said form constructed of a perforated material, a warm air chamber, said body form mounted above said chamber, an inflation bag enveloping said body form, auxiliary inflation bags attached to said main bag, a steam chamber positioned within said body form, said steam chamber provided with an inlet at its lower end, an outlet at its upper end and a drain at its extreme bottom, a perforated baffle plate positioned within said steam chamber above said inlet, said steam chamber connected with a source of steam supply, a valve arrangement incorporated within the tube leading from the outlet of said chamber, a plurality of perforated downwardly disposed tubes leading from said valve, means for manually operating said outlet valve, a blower, a motor, current supply leading to said motor for actuating said blower, both the blower and motor positioned within said warm air chamber, a radiator unit forming an inlet for said blower, said radiator unit heated by means of the steam supply, the outlet of said blower exhausting the warm air into the said chamber, a partition within said warm air chamber, said partition provided with a damper, means for operating the damper thereby permitting the warm air to leave said chamber and enter said inflation bag when the blower is being operated.

2. A device of the character described comprising in combination a foraminous body form, a warm air chamber, said form rotatably mounted to said warm air chamber, an inflation bag constructed of fabric attached to said warm air chamber and enveloping said body form, a pair of auxiliary inflation bags closed on their depending ends and open at their point of attachment to said inflation bags, a steam chamber centrally disposed within said body form, said steam chamber provided with a source of steam supply, an outlet at its upper end and a drain at its lower end, a perforated baffle arranged within the steam chamber at a point above the steam supply, a valve arranged onto the outlet tube of said steam chamber, a plurality of downwardly disposed tubes leading from said valve, said tubes provided with perforations for the escape of said steam when said valve is open, means for manually operating said steam outlet valve, a blower having an inlet and outlet port, a motor for actuating said blower, a radiator unit connected to the inlet port of said blower, said radiator unit heated by means of steam supply, said blower exhausting the warm air through its outlet into said warm air chamber, a partition within said warm air chamber, said partition provided with perforations, a damper mounted onto said partition, said damper provided with perforations, means for operating said damper to permit registration of the perforations and leads for conveying current to said motor for the operation of said blower.

3. A device as described in claim Number 2 provided with a clamp arrangement to support a garment in position when applied over the body form, to permit proper adjustment when the warm air is blown from the warm air chamber to the inflation bag.

4. A device of the character described comprising a body form, a warm air chamber, means

for rotatably mounting said body form to said warm air chamber, an inflation bag attached to said warm air chamber and entirely enveloping said body form, both body form and inflation bag constructed of a porous material thereby permitting said bag to expand when inflated within the limits provided by a garment placed over said body form, two auxiliary inflation bags constructed of similar material disposed for engagement with the insides of the sleeves of said garment, said auxiliary bags having their depending ends closed and the point of attachment open to said inflation bag, a steam chamber provided with a supply and exhaust, said steam chamber positioned within said body form, a perforated baffle plate arranged within said steam chamber above the inlet port, a drain for said steam chamber at its extreme bottom to lead off the condensation, a valve in the upper exhaust tube of said steam chamber, a plurality of tubes downwardly disposed and arranged parallel to the outer sides of said steam chamber, leading from said valve said tubes provided with apertures and closed at their lower end, a radiator unit, said radiator unit heated by means of said steam supply, a blower having an inlet and outlet port, the inlet port connected to said radiator unit, the outlet port connected to said warm air chamber, a motor for actuating said blower, the operation of said blower drawing in warm air through the radiator unit and exhausting it through its outlet to the warm air chamber, a damper arrangement between the said warm air chamber and said inflation bag and means for controlling the supply of steam within said steam chamber, means for operating said exhaust valve on said steam chamber and means for permitting the air from the warm air chamber to enter said inflation bag to dry the garment after said garment has been impregnated with said dry steam.

5. A device as described in claim 4 provided with an auxiliary clamping devices to retain the garment in a fixed position while the inflation bag is in the expanded position.

6. Garment conditioning apparatus comprising a base portion, a vertical torso-shaped member supported thereon, a substantially closed bag of permeable fabric encompassing such member and supported from the upper part thereof and adapted to be inflated inside the garment to be conditioned, said member and said fabric being rotatable about a substantially vertical axis with respect to said base portion, and means supported in said base portion and extending into said member for passing steam through said member, fabric and garment for conditioning the latter.

7. Garment conditioning apparatus comprising a base portion, a substantially vertical form member rotatably supported on said base por-

tion, a substantially closed bag of permeable fabric encompassing such member and supported from the upper part thereof for rotation therewith, said bag having auxiliary bag members to serve as arms and being adapted to be inflated inside the garment to be conditioned, and means supported in said base portion and extending into said member for passing heated fluids through said member, fabric and garment for conditioning the latter.

8. Garment conditioning apparatus comprising a base portion, a substantially vertical torso-shaped foraminous member supported thereon and in communication therewith, a closed bag of permeable fabric encompassing such member and adapted to be inflated inside the garment to be conditioned, said member and said fabric being rotatable with respect to said base portion and means for passing heated fluids through said member, fabric and garment for conditioning the latter, said means comprising a plurality of steam nozzles inside of said member and a source of heated air in said base portion adapted to be supplied under pressure to said member.

25 9. Garment conditioning apparatus comprising a base portion, a substantially torso-shaped foraminous member rotatably supported on said base portion, and in communication therewith, a substantially closed bag of permeable fabric encompassing such member and supported from the upper part thereof, the lower edge of said fabric being rotatably supported on said base portion, said bag being adapted to be inflated inside the garment to be conditioned, a steam separator having a plurality of conduits leading from the dry steam side thereof inside of said member and a plurality of nozzles therein adapted to supply dry steam substantially along the whole length of the member, means for supplying heated air from said base portion to said member and means for regulating such supply, whereby dry steam and heated air may be passed through said member, fabric and garment for conditioning the latter.

40 10. Garment conditioning apparatus comprising a base portion, a substantially vertical torso-shaped member supported on said base portion, a permeable fabric casing encompassing said member and secured to the upper portion thereof and adapted to inflate all portions of the garment placed thereon, means in said base portion for supplying steam and heated air to said member, said member having one or more openings therein whereby such steam and air may be passed through said member, fabric and garment for conditioning the latter, said member and fabric being rotatable with respect to said base portion whereby the garment may be rotated during conditioning.
